S. KRUK.
PERCUSSION FUSE.
APPLICATION FILED JAN. 11, 1917.

Patented July 10, 1917.

RECEIVED

UNITED STATES PATENT OFFICE.

Stanley Kruk, of Clymer, Pennsylvania.

PERCUSSION-FUSE.

1,232,814. Specification of Letters Patent. Patented July 10, 1917.

Application filed January 11, 1917. Serial No. 141,864.

To all whom it may concern:

Be it known that I, STANLEY KRUK, a citizen of the United States, residing at Clymer, in the county of Indiana and State of Pennsylvania, have invented certain new and useful Improvements in Percussion-Fuses; and I do declare the following to be full, clear, and exact description of the invention, such as will enable others skilled in the art to which it appertains to make and use the same.

This invention relates to new and useful improvements in fuses for dynamite charges used in blasting, and more particularly to the class of fuse known as percussion fuses, and the primary object of the invention is to provide a fuse of this character which may be safely transported, handled, and used.

Another object of the invention is to provide a device of this character which is simple and durable in construction, inexpensive to manufacture, and one which will be very efficient in operation.

With these and numerous other objects in view, my invention consists of the novel features of construction, combination and arrangement of parts which will be herein referred to and more particularly pointed out in the specification and claims.

In the accompanying drawings:

Figure 1 is a side elevation of my improved form of fuse, showing the same in operative position;

Fig. 2 is a central vertical section through the fuse;

Fig. 3 is a cross section on the line 3—3 of Fig. 2;

Fig. 4 is a cross section on the line 4—4 of Fig. 2;

Fig. 5 is a cross section on the line 5—5 of Fig. 2;

Fig. 6 is a detail view of the firing pin; and

Fig. 7 is a side elevation of the fuse, parts thereof being broken away and showing in detail the pull wire connection with the fuse casing.

In describing my invention, I shall refer to the drawings in which similar reference characters designate corresponding parts throughout the several views. The numeral 1 designates the casing of the fuse which is substantially tubular and which is contracted toward one end. The larger or up-

per end of the casing is provided with a cap 55 or closure 2, which is firmly secured thereto by soldering 2', or any other desired means and the lower end 3 of the casing is left open.

Positioned longitudinally within the casing 1 is a firing pin 4 which is formed with an opening 5 disposed adjacent its upper end, that is, the end of the pin that is disposed adjacent the closed end of the casing. The other end of the pin is disposed adjacent the closed end of the casing. The other end of the pin is pointed and is provided with spurs 4' thereon to insure its operation. The cap 2 is provided with a central opening 5' through which the upper end of the firing pin is positioned, when said pin is operatively disposed. The pin 4 is formed with a stop member 7' thereon intermediate its ends which preferably comprises an annular projecting ring, and surrounding the upper end of the pin is a coil spring 6 which has its lower end positioned in a washer 7 which is adapted to be positioned against the stop ring 7' as clearly shown in Fig. 2 of the drawings. The upper end of the coil spring 70 6 is adapted to normally, when released, be positioned against the cap 2 at this end of the casing. However, when the spring is contracted, this end of the same will be positioned beneath the upper end of the pin, in 75 a manner to be hereinafter more fully described.

Intermediate the ends of the casing is positioned a partition 8, having a centrally disposed guide opening disposed therein, 80 through which the lower or front portion of the pin 4 is adapted to slide. When the firing pin 4 is in retracted or operative position, the stop member 7 on the same is positioned a short distance from the partition 8, and 85 when the pin is released, the same will be guided in its movement by the partition. In the front end of the casing 1 is an explosive cap 11 formed of some detonating material such as fulminate, dynamite, nitro-glycerin 90 or other explosive composition, suitable for effecting the firing of a blasting charge. This cap 11 is disposed directly in the path of the pin 4 and is exploded when the pin pierces the same. The inner end of the cap 11 against which the end of the pin is projected, has positioned thereon a priming cap 11', such as is common in devices of this

character. Owing to the fact that the forward or lower end of the casing 1 is contracted, the explosive cap will be securely positioned therein.

- 5 Projecting through an opening 12 adjacent the edge of the cap 2 at the upper end of the casing 1, is a pull wire 13. This pull wire has its inner end extending a short distance within the casing 1 and is bent to form
 10 a hook 14, said hook being adapted to be positioned through the opening 5 at the upper end of the pin, when said pin is retracted against the tension of the coil spring that surrounds the upper end of said pin.
 15 The extremity of the hooked portion 14 of the pull wire is adapted to be positioned in an opening 15 in the side of the casing 1, this opening being preferably formed by coacting notches in the edge of the cap 2, and
 20 upper edge of the casing. When the hooked portion 14 of the pull wire is positioned through the upper end of the pin, the coil spring is compressed, and the upper portion of the same will rest against the wire. The
 25 firing pin 4 is lifted or contracted to the position shown in Fig. 2 of the drawings to enable the hook to pass through the upper end of the same and when in this position, it will be held retracted against the tension
 30 of the coil spring.

In operation, when the various parts of the fuse are assembled as shown in Fig. 2 of the drawings, it will be seen that the firing pin is retracted against the tension of
 35 the coil spring, which will exert a constant forward pressure on the same, and also a tension against the hooked portion 14 of the pull wire. However, this wire is of sufficient strength to normally hold the pin lifted or
 40 retracted, and the said hooked portion is additionally strengthened by having its extremity disposed in the opening through the side of the casing. When in this position, the pointed lower or forward end of the
 45 firing pin will be spaced a short distance above the explosive cap 11 in the open end of the casing.

To operate the fuse when the parts are in the above described position, and after the
 50 fuse has been placed in a blasting charge, the pull wire 13 is drawn outwardly with sufficient tension exerted thereon to disengage the hooked portion 14 from the upper end of the firing pin, and withdraw the same
 55 through the cap 2 that closes the upper end of the casing. This will release the firing pin, and the same will be projected forwardly or downwardly by the expansion of the coil spring, thereby exploding the cap
 60 11 that is disposed directly in the path of this forward movement. The partition 8 forms a guide for the forward movement of the pin, so that it will strike squarely on the primer that is secured to the inner face of
 65 the explosive cap.

As is usual in devices of this character, the pull wire is tamped down, and the same is operated by means of a long rope cable, whereby the fuse may be fired when the operator is at a safe distance from the blasting charge. The hooked member, when positioned through the opening in the upper end of the firing pin, will form a positive lock for the contracted spring and the outward tension of this spring exerted on the hooked portion will likewise securely hold the same within the casing and prevent the fuse from being fired prematurely. The tension of the coil spring is not sufficient to straighten out the hook, but rather tends to 70 lock the same in position, so that it takes considerable outward pull on the wire 13 to release the parts. If desired, the extremity of the hooked portion is disposed through the side of the casing adjacent the upper 75 edge of the same and may be soldered thereto when the cap is soldered to said casing. This will form an additional securing means to prevent the hook from becoming accidentally disengaged from the retracted pin. 80

From the foregoing description of the construction and operation of my improved fuse, the manner of applying the same to use, and the operation thereof will be readily understood, and it will be seen that I 85 have provided a simple and efficient device of this character for carrying out the objects of the invention.

I claim:

1. A device of the class described comprising a tubular casing having one end closed, an explosive cap disposed in the open end of said casing, a firing pin positioned longitudinally in the casing and having an opening in its upper end, a pull wire extending a short distance through the closed end of the casing, a hook on the inner end of said wire adapted to pass through the opening in the upper end of the firing pin and having its extremity positioned in the side 100 of the casing, said hook being releasable upon the outward movement of the pull wire, and means for projecting the pin forwardly upon release of the same from the pull wire to explode the cap. 105

2. A device of the class described comprising a tubular casing having one end closed, an explosive cap disposed in the open end of said casing, a firing pin positioned longitudinally in the casing and having an opening in its upper end, a coil spring surrounding the upper end of said pin, a stop on the pin adapted to engage the lower end of the spring, a partition adjacent the cap in the open end of the casing having a guide opening therethrough in which the pin is positioned, a pull wire extending a short distance through the closed end of the casing, a hook on the inner end of said wire adapted to pass through the opening in the upper 110 115 120 125 130

end of the firing pin when said pin is retracted against the tension of the coil spring, said hook having its extremity positioned in the side of the casing, and the hook being releasable upon the outward movement of the pull wire, whereby the pin is projected forwardly to explode the cap.

In testimony whereof I have hereunto set my hand in presence of two subscribing witnesses.

STANLEY KRUK.
